UNITED STATES PATENT OFFICE.

JOHN KIRBY, JR., OF DAYTON, OHIO, ASSIGNOR TO THE DAYTON MANUFACTURING COMPANY, OF DAYTON, OHIO, A CORPORATION OF OHIO.

CAR-BRAKE MECHANISM.

1,266,278.

Specification of Letters Patent. Patented May 14, 1918.

Application filed November 15, 1917. Serial No. 202,142.

To all whom it may concern:

Be it known that I, JOHN KIRBY, Jr., a citizen of the United States, and resident of Dayton, in the county of Montgomery and State of Ohio, have invented a certain new and useful Improvement in Car-Brake Mechanism, of which the following is a description, reference being had to the accompanying drawings, which form a part of my specification.

My invention relates to an improvement in car brake mechanism, and more particularly to that class wherein the handle or operating lever when turned in one direction rotates the brake-shaft, and when turned in an opposite direction will move independently of the brake-shaft. The invention further relates to brake operating mechanism wherein the normal or inoperative position of the operating lever is substantially parallel with the brake-shaft and wherein the operative position of said lever is at right angles to the shaft.

The object of my invention is to produce a brake operating mechanism wherein a ratchet wheel is fixed to or formed on the brake-shaft and a spring actuated ratchet engaging member is mounted on the operating lever in such manner as to permit it to engage either of the teeth of the ratchet wheel to rotate the brake-shaft in a winding direction to apply the brakes, and to automatically move out of the path of said teeth when the operating lever is moved in the opposite direction, and when the latter is dropped to its normal position parallel with the brake-shaft.

With the aforesaid and other objects in view the invention consists in the various novel details of construction and combination of parts, hereinafter fully described in the specification, illustrated in the drawings and more particularly pointed out in the claims.

In the accompanying drawings forming part of the specification, and in which like reference characters indicate corresponding parts, I have illustrated one form of brake operating mechanism embodying the essential features of my invention, although the same may be carried into effect in other ways without in the least departing from the spirit thereof.

In the said drawings:

Figure 1 is a side view of the device

partly in elevation and partly in section taken on the line A—A in Fig. 2, the operating lever being shown in its operative position by solid lines and in its inoperative position by dotted lines.

Fig. 2 is a top plan view of Fig. 1, the sectioned portion being taken on the line B—B of Fig. 1.

Fig. 3 is a broken side view of the connecting end of the operating lever detached.

Fig. 4 is a perspective view of the ratchet engaging member detached.

Fig. 5 is a sectional view through the lateral chamber showing the restraining device and the adjacent extension with which it coöperates to hold the operating lever against dropping of its own weight.

Referring to the drawings, 1 is the brake-shaft, the lower portion of which may be journaled in the car platform in the usual manner, and it may be provided with the customary pawl and ratchet wheel mounted on the platform to hold the brake-shaft against retrograde movement during the process of setting the brakes and thereafter until the pawl is released by the foot of the operator. This mechanism is not shown for the reason that it constitutes no part of my invention and is familiar to all those having knowledge of such matters. 2 is a ratchet member mounted upon and rigidly secured to the shaft, in the present instance by means of pins 3, 4, which pass through the ratchet member 2 and the shaft 1, although this ratchet member may be formed integral with the shaft in lieu of forming it in a separate piece. In order to reduce the ratchet member to a diameter which shall not be objectionable the shaft is reduced at 5 and the hole through the ratchet member is made to conform therewith. The ratchet member 2 is provided with a series of vertically disposed teeth 6 arranged around its periphery immediately opposite the reduced portion of the shaft and which terminate below the upper end of the said member, leaving a portion 7 of the latter extending above the teeth to receive the pin 3, as shown in Fig. 1.

Surrounding the ratchet member 2 and resting upon the top thereof there is loosely mounted upon the shaft a sleeve member or cylinder 8 held in place on the shaft by a nut 9 which engages a reduced threaded end 10 thereof. This sleeve is adapted to be rotated in either direction independently of

the shaft and it is provided, at one side thereof, with lateral extensions 11, 12, having a top portion 13 forming an extension of the top of the sleeve, the wall of which is 5 cut away between the said lateral extensions. The said extensions together with a front portion 14 form a housing for an operating lever about to be described, the lower edge of the portion 14 forming a stop which limits the upward movement of said lever. An 10 operating lever 15 is pivotally mounted upon and between the said lateral extensions by means of a bolt 16 which passes through the said extensions and through the operating 15 lever having a head 17 at one end and a perforation to receive a cotter pin 18 at the opposite end, to prevent undue displacement of the bolt. The operating lever being thus pivotally mounted when in its normal or inoperative 20 position hangs suspended upon the pivot bolt 16 substantially parallel with the shaft as shown by dotted lines in Fig. 1, and when in operative position the lever occupies a horizontal position, as shown by solid lines 25 in said Fig. 1. The operating lever is in part hollow and at its connecting end forms a chamber in which there is mounted a ratchet engaging member or vertically disposed spring actuated pawl 19 operative 30 upon a pintle 20 screwed into and through the top wall of the lever and passing down through the body 21 of the pawl into and through the bottom wall of the lever. The free end of this pawl extends outwardly 35 through the open end of and beyond the end of the operating lever and engages behind the teeth 6 of the ratchet member 2 as the latter is rotated in a direction to set the brakes, which operation is accomplished by 40 turning the operating lever in the direction indicated by the arrow in Fig. 2. When the stroke is completed the operator reverses the movement of the lever and takes a fresh grip during which operation the pawl 19 45 rides over the inclined surfaces of the teeth, being forced there-behind through the medium of a coil spring 22 having one end bearing against a shoulder 23 of a plug 24 screwed through one of the side walls of 50 the operating lever and its opposite end exerting pressure against an arm 25 of the pawl 19 having a concaved recess 26 in which the semispherical surface of a head-piece 27 attached to the spring operates, 55 movement of the pawl being limited by shoulders 28, 29 at the end of the operating lever, as best shown in Fig. 2.

It is to be understood that my invention 60 contemplates setting the brake through a number of partial revolutions of the brake-shaft, that is to say, one stroke of the operating lever will rotate the shaft, say, one-quarter of a revolution, the lever then being reversed for another stroke, the operation 65 being repeated until the brakes are fully set,

each partial revolution of the shaft being held against retrograde movement by the pawl and ratchet mechanism on the floor of the platform and to which reference has hereinbefore been made.

It sometimes happens that when the brakes are set and the retaining pawl and ratchet previously referred to is released, the shaft refuses to unwind because of irregularity. In such cases it becomes necessary to use force to free the brake chain and allow the shaft to perform its proper function. To provide for such emergency and adapt the mechanism of my present invention to the performance of such reverse action I provide a pin 30 adapted to be inserted through a perforation 31 in the extension 13 of the sleeve 8 and through a corresponding perforation, not shown, in the top wall of the operating lever down 85 through a similar perforation 32 in the bottom wall of said lever immediately behind the pawl 19 so as to lock the same in engagement with its co-acting ratchet tooth and thus provide a means whereby the shaft 90 may be operated in a reverse direction. A support 33 is provided for the pin when out of service, and a chain 34 secures it against removal from the brake mechanism.

The operating lever is provided with a lateral chamber 35, so located as to be within the space formed between the lateral extensions 11, 12 whatever may be the position of the said lever. Within this chamber there is located a spiral spring 36 having one end bearing against the bottom of the chamber and its other end being provided with a rounded head-piece 37 having a shoulder 38 to receive the adjoining end of the spring which, when the operating lever is 100 in operative position presses the head-piece 37 outward into a corresponding detent 39 formed in the inner surface of the extension 11 of the sleeve 8, the purpose of this feature of the invention being 105 to restrain the operating lever from dropping of its own weight while in operative position, thus relieving the operator from the necessity of holding the said lever up against its inclination to drop to its normal 110 position during the brake setting operation, it being understood that a slight pressure on the lever will release the spring pressed head-piece and leave the lever free to drop by gravity to its normal position. This particular feature of my invention is not necessarily confined to the brake operating mechanism herein described but is applicable also to other types in which drop handle or operating levers are employed.

To operate the foregoing described winding mechanism the operator raises the operating lever from its normal or inoperative position to its operative or horizontal position, in doing which the spring actuated 130

pawl being mounted in the said lever will automatically swing into position behind one of the ratchet teeth and establish operative connection with the brake-shaft which 5 can then be rotated by turning the operating lever, the said operative connection being broken by the dropping of the operating lever, which in swinging to its normal or vertical position carries with it the spring 10 actuated pawl and frees the same from engagement with the ratchet teeth, leaving the brake-shaft free to unwind when not held against retrograde movement by means employed for that purpose.

15 Having thus fully described my invention, I claim:—

1. In car brake mechanism, the combination of a shaft adapted to be rotated, a ratchet carried by the shaft and rotatable therewith, the member mounted upon the shaft and rotatable thereon independently thereof, an operating lever in pivotal connection with said member, and a vertically disposed spring actuated member pivotally 25 mounted upon said operating lever adapted to engage said ratchet whereby the shaft may be rotated.

2. In car brake mechanism, the combination of a shaft adapted to be rotated, a ratchet carried by the shaft and rotatable therewith, a member mounted upon the shaft and rotatable thereon independently thereof, an operating lever in pivotal connection with said member, and a vertically 35 disposed spring actuated pawl pivotally mounted upon said operating lever adapted to automatically engage said ratchet whereby the shaft may be rotated.

3. In car brake mechanism, the combination of a shaft, a ratchet carried by and rotatable with the shaft, a member mounted upon the shaft and rotatable independently thereof, an operating lever in pivotal connection with said member, and a vertically 45 disposed spring actuated pawl pivotally mounted upon said operating lever adapted to engage the teeth of said ratchet whereby said lever when turned in one direction will rotate the shaft and when turned in the opposite direction will move independently of the shaft.

4. In car brake mechanism, the combination of a shaft, a ratchet carried by and rotatable with the shaft, a member mounted upon the shaft and rotatable independently thereof, an operating lever in pivotal connection with said member, and a second member comprising a vertically disposed pawl pivotally mounted upon said 55 operating lever and adapted to swing in and out of engagement with the teeth of said ratchet with the raising and lowering of said operating lever; whereby when said lever is turned in one direction the 60 shaft will be rotated and when turned 65

in the opposite direction said lever and said second member will move independently of the shaft.

5. In car brake mechanism, the combination of a shaft having a ratchet therearound, 70 of a member mounted upon said shaft and rotatable thereon independently thereof, an operating lever pivotally mounted upon said member, and mechanism comprising a vertically disposed spring actuated pawl 75 pivotally mounted upon said lever and adapted to automatically establish operative connection between said lever and said shaft whereby the same may be rotated.

6. In car brake mechanism, the combination of a shaft and a ratchet adapted to be rotated, a member mounted upon the shaft and rotatable independently thereof, an operating lever in pivotal connection with said member and having an elevated operative 80 position and a depending normal position, and vertically pivoted pawl mechanism mounted on said lever arranged to engage said ratchet when the lever is elevated and thereby establish operative connection with 85 the shaft to rotate the same; the said connection being broken by the downward movement of the lever.

7. In car brake mechanism, the combination of a shaft, a circular member having 90 ratchet teeth formed in its peripheral surface carried by and rotatable with said shaft, a second member carried by and rotatable independently of the shaft, an operating lever in pivotal connection with said second member being normally suspended upon its pivot and adapted to be swung to a horizontal position, and a vertically arranged spring actuated ratchet engaging member pivotally 95 mounted upon said operating lever whereby 100 in raising the same to a horizontal position operative connection between the shaft and said lever will be established, said connection being broken by the downward movement of the lever.

8. In car brake mechanism, the combination of a shaft having a ratchet adapted to be rotated, a member mounted upon said shaft and adapted to be rotated independently thereof, an operating lever in pivotal 115 connection with said member and normally suspended upon its pivot, a chamber formed in one end of said operating lever, and a vertically disposed spring actuated ratchet engaging member pivotally mounted upon 120 said lever within said chamber; whereby when said lever is raised to a horizontal position said ratchet engaging member will automatically engage said ratchet and thereby establish operative connection between 125 said shaft and said lever.

9. In car brake mechanism, the combination of a shaft having a ratchet adapted to be rotated, a member mounted upon said shaft and adapted to be rotated independ- 130

ently thereof, an operating lever in pivotal connection with said member and normally suspended upon its pivot, a chamber formed in one end of said operating lever, a vertically disposed ratchet engaging member pivotally mounted upon said lever within said chamber, and yieldable means for forcing said ratchet engaging member into operative engagement with said ratchet.

10. In car brake mechanism, the combination of a rotatable shaft and ratchet, a sleeve loosely mounted upon the shaft and having members extending laterally therefrom, an operating lever pivotally mounted upon said lateral members and normally suspended upon its pivot, and vertically disposed spring actuated mechanism pivotally mounted upon said operating lever adapted to engage said ratchet and thereby establish operative connection with the shaft whereby the same may be rotated.

11. In car brake mechanism, the combination with a shaft provided with means for its rotation, a member mounted upon and rotatable independently of the shaft, an operating lever in pivotal connection with said member and normally suspended upon its pivot, vertically disposed spring actuated mechanism pivotally mounted upon said lever and adapted to swing into and out of engagement with said means and thereby establish operative connection whereby said shaft may be rotated, and a device for locking said mechanism in operative connection with the shaft whereby the latter may be rotated in either direction.

12. In car brake mechanism, the combination with a shaft provided with means for its rotation, of a member mounted upon and rotatable independently of the shaft; said member having lateral extensions forming a support for an operating lever, an operating lever pivotally mounted upon said extensions and normally suspended upon its pivot, vertically disposed spring actuated mechanism pivoted on said lever and adapted to swing into and out of engagement with said means and thereby establish operative connection whereby said shaft may be rotated, and a removable pin adapted to lock said mechanism in operative engagement with the shaft whereby the latter may be rotated in either direction.

13. In car brake mechanism, the combination of a shaft provided with means for its rotation, a member mounted upon and rotatable independently of the shaft; said member having lateral extensions forming a sup-

port for an operating lever, an operating lever pivotally mounted upon said extensions and normally suspended upon its pivot, and means whereby the operating lever is restrained from dropping of its own weight when the lever is in operative position.

14. In car brake mechanism, the combination of a shaft provided with means for its rotation, a member mounted upon and rotatable independently of the shaft; said member having lateral extensions forming a support for an operating lever, an operating lever pivotally mounted upon said extensions and normally suspended upon its pivot, and spring actuated mechanism intermediate said extensions and said lever to restrain the lever from dropping of its own weight when in operative position.

15. A new article of manufacture comprising a chambered operating lever adapted to be pivotally connected with a brake-shaft having a ratchet thereon and to be swung in a vertical plane upon its pivot, a vertically disposed ratchet engaging member pivotally mounted in the chamber and having a branch arm extending therefrom, and spring mechanism adapted to exert pressure against said branch arm to force said member into operative engagement with said ratchet.

16. A new article of manufacture comprising a chambered operating lever adapted to rotate a brake-shaft having a ratchet thereon, a ratchet engaging member mounted in the chamber having a branch arm extending therefrom, spring mechanism adapted to exert pressure against said branch arm to force said member into operative engagement with said ratchet, and a spring device mounted in one of the walls of said operating lever adapted to retain said operating lever in an elevated position.

17. A new article of manufacture comprising a chambered operating lever adapted to rotate a brake-shaft having a ratchet thereon, a ratchet engaging member mounted in the chamber having a branch arm extending therefrom, spring mechanism adapted to exert pressure against said branch arm to force said member into operative engagement with said ratchet, means for locking said member in operative engagement with said ratchet, and a spring device mounted in one of the walls of said operating lever adapted to retain said lever in an elevated position.
